TOY JET AIRCRAFT

Donald C. Browne, Vancouver, British Columbia, Canada

Application August 2, 1954, Serial No. 31,685

Term of patent 3½ years

(Cl. D34—15)

Fig-1-

Fig-2-

Fig-3-

To all whom it may concern:

Be it known that I, Donald C. Browne, a citizen of Canada and a resident of the city of Vancouver, in the Province of British Columbia, Canada, have invented a new, original, and ornamental Design for a Toy Jet Aircraft, of which the following is a specification, reference being had to the accompanying drawings, forming a part thereof.

Figure 1 is a side elevational view of a toy jet aircraft showing my new design,

Figure 2 is a front elevational view thereof, and Figure 3 is a bottom plan view thereof.

I claim:

The ornamental design for a toy jet aircraft, as shown.
